ATTORNEY.

UNITED STATES PATENT OFFICE.

OMAR C. DE SELMS, OF ATTICA, INDIANA.

DESIGN FOR A PHONOGRAPH-CABINET.

54,201.

Specification for Design.

Patented Nov. 18, 1919.

Application filed July 29, 1919. Serial No. 314,139. Term of patent 14 years.

To all whom it may concern:

Be it known that I, OMAR C. DE SELMS, a citizen of the United States, residing at Attica, in the county of Fountain and State of Indiana, have invented a new, original, and ornamental Design for a Phonograph-Cabinet, of which the following is a specification, reference being had to the accompanying drawings, forming part thereof.

Figure 1 is a top or plan view of a phonograph cabinet, showing my new design. Fig. 2 is a perspective view of the phonograph cabinet, showing my new design.

I claim:

The ornamental design for a phonograph cabinet, as shown.

OMAR C. DE SELMS.
